US00D921118S

(12) **United States Design Patent** (10) Patent No.: **US D921,118 S**
(45) Date of Patent: **** Jun. 1, 2021**

(54) **DINOSAUR SHAPED GAME BOARD**

(71) Applicant: **Xiaobing Yu**, Guangdong (CN)

(72) Inventor: **Xiaobing Yu**, Guangdong (CN)

(73) Assignee: **Dongguan Chokway Co., Ltd.**,
Dongguan (CN)

(**) Term: **15 Years**

(21) Appl. No.: **29/767,206**

(22) Filed: **Jan. 21, 2021**

(30) **Foreign Application Priority Data**

Dec. 11, 2020 (CN) 202030761822.8

CLAIM

The ornamental design for a dinosaur shaped game board, as shown and described.

DESCRIPTION

FIG. 1 is a bottom, rear, right side perspective view of a dinosaur shaped game board showing my new design;
FIG. 2 is a top, front, left side perspective view thereof;
FIG. 3 is a front elevation view thereof;
FIG. 4 is a rear elevation view thereof;
FIG. 5 is a left side elevation view thereof;
FIG. 6 is a right side elevation view thereof;
FIG. 7 is a top plan view thereof; and,
FIG. 8 is a bottom plan view thereof.

1 Claim, 6 Drawing Sheets
